CLAIM

The ornamental design of an overflow water containment pedestal or similar article, as shown.

DESCRIPTION

FIG. 1 is a top perspective view of an overflow water containment pedestal or similar article showing my new design;

FIG. 2 is a top plan view thereof; and

FIG. 3 is a side elevational view thereof; the undisclosed side portions are identical to the side shown.
The undisclosed bottom of the design is substantially flat, plain and unornamented.

FIG. 1

FIG. 2

FIG. 3
